UNITED STATES PATENT OFFICE.

BENJAMIN J. WILSON AND ALBERT A. WOOD, OF ATLANTA, GEORGIA;
SAID WOOD ASSIGNOR TO SAID WILSON.

BRICK-MACHINE.

SPECIFICATION forming part of Letters Patent No. 376,460, dated January 17, 1888.

Application filed March 25, 1887. Serial No. 232,453. (No model.)

To all whom it may concern:

Be it known that we, BENJAMIN J. WILSON, a subject of Her Majesty the Queen of Great Britain, and ALBERT A. WOOD, a citizen of the United States, residing at Atlanta, in the county of Fulton and State of Georgia, have invented a new and useful Brick-Machine; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of brick-machines in which the bricks are made from dry or semi-dry clay, having especial reference to an improved brick-machine application for Letters Patent for which was made by the said Benjamin J. Wilson on the 30th day of June, 1886, and is No. 206,753 of the series of 1880.

The object of this invention is to so improve several of the details shown in that application as to make the machine more simple, durable, and more easily operated.

The invention consists, briefly, of an improved arrangement of the toggles, improved construction of the molds and forms of dies, mechanism for moving the charger, pressing the bricks, and pushing them out of the molds, also other details, as will be hereinafter fully set forth.

In the accompanying drawings, Figure 1 is a side elevation showing the gearing, actuating-crank, the toggles, the cam-arm, and connection for moving the charger, the crank for regulating the holding capacity of the molds, and a portion of the cam for pushing the bricks out of the molds and the driving-pulley, the clutch being shown in other figures. Fig. 2 is a vertical cross-section through the beam, dies, the molds, the table, the charger, and hopper, and showing the means by which the motion is communicated from the rock-shaft of the cam-lever to the charger, and the guides in which the slides on the beam run, as well as a portion of the frame. Fig. 3 is a horizontal section on the line $\alpha\alpha$, Fig. 2, showing the frame, the guides, and a portion of the beam

with the slides. Fig. 4 shows a girder for the end of the frame nearest which it is shown in the drawings. Fig. 5 is a view of the right-hand end of the machine as shown in Fig. 1, partly in section, showing the beams, dies, molds, rock-shaft, connecting-rods, and other parts, but not showing the gearing or the pulley, or those parts of the machine that are near the left-hand end of Fig. 1. Fig. 6 is a vertical section on the line yy , Fig. 5, showing the cam and swinging arm by which the cam and lower arm are raised to push the bricks out of the molds and the wedge and screw by which the holding capacity of the molds is governed. Fig. 7 is a detail showing the rolling-fulcrum, which is attached to and forces upwardly the lower beam. Fig. 8 is a side view of the upper die and a brick, the brick being in central section. Fig. 9 is a vertical cross-section through the upper die and a brick, passing through two opposite vent-holes in the die. Fig. 10 is a view of the molds, partly in section. Fig. 11 is a brick in perspective, showing the panel in the top. Fig. 12 is one side of the clutch and belt-pulley, showing the end of the shaft. Fig. 13 is a side view of the clutch and belt-pulley, partly in section. Fig. 14 is a view of the inner side of the clutch-pulley. Fig. 15 is a horizontal section on the line zz , Fig. 14.

In the figures, like reference-marks referring to like parts in the several views, the parts shown are as follows:

The sills A are shown in Figs. 1, 5, and 6, and the upright parts B of the frame are shown in the same figures and also in Figs. 2 and 3. These sills and uprights, with the braces C, Fig. 1, and the girders a and a', Figs. 4, 5, and 6, and b and b', Figs. 1, 2, 5, and 8, form the frame. On the sills A is journaled the rock-shaft D, Figs. 5 and 6. This rock-shaft has at each end projecting cranks d and d', and near its center cranks e. The pin F of the crank d passes through the arms of both these cranks, being tied to the rock-shaft by the arm f, and the outer ends forming journals for the connecting-rods G. The pins h pass through the cranks d' and e, each connecting a crank d' and a crank e, and forming on the outer end journals for the fulcrums H and on

the inner end journals for the arms J of the horizontal toggle composed of the arms J and K.

Between the inner ends of the pins h is a sufficient space for the swinging arm L, by contact with which the cam raises the lower beam and pushes the bricks out of the molds, the cam being prevented from pushing the arm beyond a vertical position by the roller 10 N, journaled on the girder b'. A portion of the surface of the cam M is composed of the arm m, hinged at one end to the cam M by the pivot m' and adjustably secured at the other end by the bolt n and the washers n'. The 15 toggle J K is journaled at the end opposite the pins h on the pin O, which is secured in its open boxes by the eyebolts q, Fig. 1, thus carrying the strain of this toggle to a point on the frame near the journal-box of the rock- 20 shaft D. On the knuckle-pin of the toggle J K is journaled the pitman P, which connects it with the crank Q. Motion is communicated to the crank Q from the pulley R by gearing, the pulley R being loose on the shaft v and 25 driving that shaft by means of the clutch shown in Figs. 12, 13, 14, and 15. The inner side of the rim of the pulley R is the surface for the frictional contact of the segments s. Each of the two segments marked s has a radial slide, S, 30 which slides in a rectangular opening in the rim S', which otherwise resembles a pulley-rim, on the outer or projecting side of which (see Fig. 13) may be applied a brake. The levers U are hinged to the inner ends of the 35 slides S, and have as fulcrums the pins u' in the lugs u, and at the outer end are hinged to the forked arms V, into which are secured the extension-pieces v, which are provided at their abutting ends with hooks v'. In a circular 40 opening in the end of the shaft of the pulley R is a loosely-fitted plug, W. Near the inner end of the plug W is a mortise, and in the shaft is a corresponding, though somewhat longer, mortise, into which the extension-pieces v enter and meet, the hooks v' entering the recess in the slot, as shown in Fig. 13. The drawing outwardly of the plug W will draw inwardly the segments s, when the pulley running 45 loosely will not turn the shaft. On the plug being pushed inwardly to the position shown 50 in Fig. 13 the toggle-arms V will be straightened and force the segments into contact with the inner surface of the rim-pulley R with sufficient pressure to produce enough friction 55 to cause the pulley to turn its shaft.

It is desirable that the toggles V should straighten in order that they will not force the plug outwardly by the force coming from the segments s, which may be insured by the 60 screwing out or in of the extension-pieces v.

The crank-pin F is connected to the pin t, extending through the upper beam, B, Figs. 1, 2, and 5, by the pitmen G. The wrists h carry the rollers h', which engage with the 65 lower ends of the rolling-fulcrums H. The rolling-fulcrums are pivoted to the pins c', Figs. 1, 2, and 5, in the lower beam, C, and

have downwardly-projecting arms H'', Figs. 1 and 7, to insure the engagement of the roller with its lower end.

On the central portion of the rock-shaft is a cam, which consists of the segmental part having a uniform radius, and the adjustable part m, hinged on the pivot m' and adjusted by means of the washers n' and bolt n, Fig. 6. Attached to the lower beam is the arm L, which has a roller at its lower end, and is pivoted at its upper end to the beam. The dies being closed, as shown in these figures, to open them the rock-shaft revolves backwardly, as shown 80 by the arrow, Fig. 6, and, carrying the cam M against the roller in the arm L, raises the beam C, and with it the dies, thus forcing the bricks out of the top of the molds. The roller N prevents the arm being forced back by the 85 cam beyond a vertical position when forcing the bricks out. A portion of the cam is a segment of a circle which causes the beam, while the roller is passing over the segment, to remain stationary a sufficient length of time to 90 allow the bricks to be pushed off of the dies, as will be hereinafter fully described, and the segment is of such length only as will permit it, in that backward movement, to pass entirely out from under the roller l, thus allowing the roller to drop back on the wedges D', which, by adjustment, will govern the height 95 at which the beam stops. The rock-shaft in all of its movements is actuated by the crank Q through the pitman P and toggle J K, and 100 in the backward movement just described will raise the upper beam, B', to a height that will allow the charger to pass under.

It will be observed in Fig. 1 that the rollers f' are placed on journals on the ends of the pins t through the upper beam. These rollers work in slotted cams in the arms F' that are fastened to the shaft E'. To the shaft E' are also fastened the arms e', which are connected at their lower ends by links g to the charger 110 G'. This charger receives a supply of clay from the chute H', and operates substantially the same as that shown in the application of B. J. Wilson, hereinbefore referred to, but is actuated by a vertical movement of the upper 115 beam, B', through the roller f', the cams in the arm F', the rock-shaft E', the arms e', and the links g, the charger being allowed to rest for a short time under the chute by the parallelism of the faces of the lower part of the cam 120 and the line of motion of the roller f'.

The series of molds in which the bricks are pressed are formed of two side pieces, K', the partition-pieces J', the end pieces, I', the Babbitt or other easily-melted metal, h, and the 125 bolts i and j. The end pieces, I', rest against the frame. The frame, being prevented from spreading by the bolts j, will prevent the spreading of these end pieces. The bolts i are somewhat tapering, and the holes through 130 which they are inserted are of about uniform size throughout their length. The partitions J' have vertical grooves in their ends, and the side pieces, K', have coincidental grooves in

their inner sides, into which a soft metal is cast to prevent the displacement sidewise of the partitions by any unequal pressure that might occur on their two sides. These vertical grooves may communicate with the holes through which the bolts *i* pass, by reason of which the Babbitt metal will fill the space around the bolts and give additional security against displacement of the partitions. These 10 molds are preferably made of chilled cast-iron, and are constructed in this way in order that the surfaces that require to be finished will have no projections.

The upper dies are marked *o* and the lower dies *p*. The upper dies have on their faces an inclined projection, *o'*, which projection is principally over the end of the mold that the charger passes over last as it enters. It is found by practice that this end of the mold 20 will contain less clay than the other, and this projection, forming the panel in the brick *x*, as shown in the brick in Figs. 2, 5, 8, 9, and 11, (best in the latter figure,) will produce the same density throughout the brick and answer all of the purposes for which brick are paneled.

The wedges *D'*, upon which the lower beam drops after the cam *M* shall have finished its work, are moved endwise, which movement 30 adjusts the lower stopping-point of the beam, and consequently the holding capacity of the molds, by the screws *r*, one of which screws is shown in Fig. 6. The screws are actuated by cranks *r'*, and are connected by the chain *r''* on 35 sprocket-wheels on the screw-shaft *r*, which causes the wedges to move uniformly with each other.

It will be observed in these drawings, as well as in the drawings in the application of 40 B. J. Wilson, hereinbefore-mentioned, that the toggles by which the rock-shafts are operated are so arranged as to exert their effective force very nearly in the line of motion of the pivot by which they are attached to the rock-shaft, 45 thereby reducing the consequent strain to a minimum, and that the power that is required to compress the clay into bricks is caused to increase in force by a system of toggles and cranks that might be used in any machine for 50 compressing any object offering an increasing resistance. It will be observed in this device that one end of the toggle has a stationary pivotal abutment, and consequently that all of

the force of the toggle is exerted on the rock-shaft.

Having thus described our invention, what we claim as new, and desire to secure by Letters Patent of the United States, is—

1. In a brick-machine, as a means of transmitting an increasing power to the upper and lower beams, the toggle *J K*, having a stationary abutment on the pin *O*, the rock-shaft *D*, having oppositely-projecting cranks on its ends, and the connecting-rods *H* and *G*, combined and operating substantially as described. 65

2. As a means of operating the reciprocating charger, the rock-shaft *E'*, having arms *e'* connected to the charger, and arms *F'*, provided with cams at their free ends, in combination with a reciprocating beam of a brick-machine, substantially as shown and described, 70 and for the purpose specified.

3. In a brick-machine, to force the bricks from the molds, the combination of the molds, 75 the beam *C'*, carrying dies *p*, the swinging arm *L*, the roller *N*, and the cam *M*, having adjustable part *m*, substantially as shown and described.

4. In a brick-machine, as a means of regulating the holding capacity of the molds, the combination of the molds and the die-carrying beams *C'* with the wedges *D'*, the screw-shafts *r*, carrying cranks *r'*, and sprocket-wheels for the chain *r''*, constructed substantially as described to operate the wedges simultaneously on both sides of the machine. 80

5. In a brick-machine, forming mechanism consisting of molds and dies, the dies for forming one side of the brick having a sloping 90 projection adapted to equalize the density of the brick pressed from clay of unequal density, substantially as shown and described.

6. In a brick-machine, a mold-box consisting of the parts *J'* and *K'*, having coincidental 95 grooves, the metal plugs *k*, and the bolts *i*, combined substantially as shown and described.

In testimony whereof we affix our signatures in presence of two witnesses.

BENJAMIN J. WILSON.
ALBERT A. WOOD.
